US00D836922S

(12) **United States Design Patent** (10) Patent No.: **US D836,922 S**
(45) Date of Patent: ** Jan. 1, 2019

(54) **FABRIC**

(71) Applicant: **Apple Inc.**, Cupertino, CA (US)
(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/578,558**

(22) Filed: **Sep. 22, 2016**

Related U.S. Application Data

(63) Continuation of application No. 29/557,214, filed on Mar. 7, 2016, now Pat. No. Des. 789,822.

(57) **CLAIM**

The ornamental design for a fabric, as shown and described.

DESCRIPTION

The sole FIGURE is a front view of a fabric showing the claimed design.

The dot-dash broken lines surrounding the figure depict the boundaries of the claim and form no part thereof. The figure is illustrated to show contrasting appearance. Areas of the fabric that appear in gray, dark gray and white represent areas with contrasting appearances.

1 Claim, 1 Drawing Sheet
